CLAIM

The ornamental design for a tube securing device base, as shown and described.

DESCRIPTION

FIG. 1 is a front perspective view of a tube securing device base according to the present design;

FIG. 2 is a bottom perspective view of the tube securing device base of FIG. 1;

FIG. 3 is a right side view of the tube securing device base of FIG. 1;

FIG. 4 is a front view of the tube securing device base of FIG. 1;

FIG. 5 is a left side view of the tube securing device base of FIG. 1;

FIG. 6 is a rear view of the tube securing device base of FIG. 1;

FIG. 7 is a top view of the tube securing device base of FIG. 1; and,

FIG. 8 is a bottom view of the tube securing device base of FIG. 1.

The broken lines depicted in FIGS. 1-8 represent unclaimed environmental subject matter and form no part of the claimed design.
